[57] **CLAIM**

The ornamental design for a flashlight, as shown.

DESCRIPTION

FIG. 1 is a side elevational view of the flashlight showing my new design.

FIG. 2 is an elevational view similar to FIG. 1 showing the flashlight rotated 90 degrees.

FIG. 3 is an elevational view similar to FIGS. 1 and 2 but with the flashlight rotated an additional 90 degrees from the position shown in FIG. 2, and 180 degrees from the position shown in FIG. 1.

FIG. 4 is a front end view of the flashlight shown in FIGS. 1—3.

FIG. 5 is a rear end view of the flashlight.
